UNITED STATES PATENT OFFICE.

LOUIS J. BORKHUIS, JR., OF VAYLAND, SOUTH DAKOTA.

GUARD FINGER AND LEDGER PLATE.

Application filed March 20, 1926. Serial No. 96,259.

This invention relates to new and useful improvements in guard fingers and ledger plates for mower sickles.

The principal object of the invention is to provide a construction of devices of this character whereby the usual inconvenient and laborious method of breaking rivets, and reriveting new ledger plates, is completely obviated.

Another object is to provide a guard finger and ledger plate construction wherein the plate is held in proper and firm position on the finger, but may be easily and quickly removed by the use of a nail, or similar instrument.

A further object is to provide a construction wherein the forward end of the ledger plate is spring pressed rearwardly into engagement with a seat, whereby said plate is positively held against displacement, or movement in any direction, accidentally.

Other objects and advantages will be apparent from the following description when taken in connection with the accompanying drawing.

In the drawing:

Figure 1 is a side elevation of a guard finger and ledger plate made in accordance with the invention.

Figure 2 is a top plan view of the same.

Figure 3 is a vertical longitudinal central sectional view through the device.

Figure 4 is a top plan view of the forward portion of the guard finger, partly broken away, and with the ledger plate removed, to show the retaining seat for said plate.

Figure 5 is a perspective view of the ledger plate removed from the guard finger.

Referring particularly to the accompanying drawing, there is shown a guard finger having the body portion 10, formed with the rear attaching portion, and the front pointed nose, shown respectively at 11 and 12, together with the upwardly and rearwardly inclined blade 13, which overlies the cavity 14, in the body of the finger. In the nose portion of the finger there is formed a bore 15, and seated in said bore is a coil spring 16. The rear of the body portion is provided with a vertical transverse wall 17, and formed in the upper face of said wall, and transversely thereof, are the recesses 18, each having its outer wall inclined upwardly and outwardly to receive thereon the beveled cutting edge of the ledger plate 19.

Intermediate these recesses 18 there is formed an upstanding lug 20, the upper face of which is in the plane of the upper face of the wall 17, and its rear edge face in the plane of the rear face of said wall. The lug extends forwardly of the wall 17, and is tapered in that direction, the apex of said lug being formed with a curved recess 21. The rear ends of the side walls of the bore 15 are cut out, as at 22, to form notches to receive the shoulders 23 of the forward end of the ledger plate 24. The rear, or wider end, of the ledger plate 24 is formed with a central V-shaped notch or recess 25, the side walls of which are beveled, at 26, to engage beneath the undercut, beveled side walls 27 of the lug 20, whereby to provide a seat for the rear end of the plate which will hold the said plate against upward movement. This seat also serves to maintain the rear end of the ledger plate against side-wise movement, as well, with the result that the plate is tightly held on the guard finger.

To remove the ledger plate from the guard finger, a suitable implement, such as a nail, is inserted in the recess 21, and proper prying action brought to bear against the lower face of the plate, with the result that the rear end of the plate will be forced upwardly and forwardly, against the tension of the spring 16, and released from the seat or lug 20, whereupon the spring will force the plate rearwardly into a position to be easily picked up by the operator.

What is claimed is:

A guard finger having a ledger plate seat having rearwardly diverging beveled side walls, a vertical lug formed centrally on the seat and having its side walls underbeveled and converging forwardly of the guard finger, the forward end of the lug having a vertical recess, a ledger plate on the seat having its rear end formed with a V-shaped recess the walls of which are beveled to properly engage beneath the converging walls of the lug, the inner angle of the V-shaped recess being disposed forwardly of the vertical recess to permit introduction of a ledger plate prying tool, and means on the guard finger for urging the ledger plate into engagement with said lug.

In testimony whereof, I affix my signature.

LOUIS J. BORKHUIS, JR.
